UNITED STATES PATENT OFFICE

MAX MULLER, OF NEW YORK, N. Y.

HAIR-WAVING.

1,254,414.

Specification of Letters Patent. Patented Sept. 28, 1920.

Application filed January 14, 1919. Serial No. 271,994.

To all whom it may concern:

Be it known that I, MAX MULLER, a citizen of the United States, and a resident of the city of New York, borough of Manhattan, in the county and State of New York, have invented new and useful Improvements in Hair-Waving, of which the following is a full, clear, and exact description.

The object of the invention is to provide certain new and useful improvements in the part of waving natural hair on the head whereby hair is permanently waved in a sidewise direction to cause the hair to lie flat on the head of the wearer in perfect Marcel wave fashion. Another object is to prevent the hair from becoming kinky or curly. Another object is to prevent the hair from becoming overheated and injured during the process of waving the hair.

With these and other objects in view the invention consists of certain novel features of construction as hereinafter shown and described and specifically pointed out in the claim.

A practical embodiment of the invention is represented in the accompanying drawings forming a part of this specification, in which similar characters of reference indicate corresponding parts in all the views.

Figure 1 is a plan view of the waving tool with a strand of hair wound upon the same;

Figure 2 is a sectional plan view of the electric heater with the waving tool, the hair wound thereon and the protecting wrapper in position in the heater, the section being on the line 2—2 of Fig. 3;

Fig. 3 is an end elevation of the same; Fig. 4 is a face view of one of the strands of hair after being wound and set and prior to being wetted and combed out; and

Fig. 5 is a side elevation of the waved hair as it appears on the owner's head.

The apparatus for producing the desired hair waving consists essentially of a waving tool 10 on which a strand of hair 11 is wound, as hereinafter more fully explained, a wrapper 12 of asbestos or a similar material inclosing the hair while wound on the tool 10, and an electric heater 13 open at the ends for receiving the wrapper 12 and the parts contained therein, as plainly illustrated in Fig. 2. The waving tool 10 is preferably made of a metal rod bent into U shape to provide side members 15 and 16 extending parallelly and connected with

each other by a bend 17, preferably covered with a covering 18 of asbestos or other suitable heat insulating material. The strand 11 is wound on the side members 15 and 16 of the waving tool 10 by passing the strand adjacent the head of the subject, first, between the two side bars 15 and 16, then around one of the bars (as shown, the bar 15) then between the bars and around the other bar 16, after which the winding as above described is repeated with the windings pushed close together, as plainly indicated in Fig. 1. The side bars 15 and 16 of the waving tool 10 are sufficiently long to accommodate practically an entire strand of hair. In practice each strand is comparatively thick so that it requires about six strands for waving the hair on the head of the subject.

The heater 12 comprises an inner metallic shell 20, an outer metallic shell 21 and heads 22 and 23 extending between the shells at the ends thereof and being securely soldered or otherwise fastened to the same thus providing an annular chamber 24 intermediate the shells. In this chamber 24 is arranged a shell 25 of mica or a similar insulating material around which is wound a resistance coil 26 of wire having its ends provided with an insulation and forming a cord extending through the head 23 to connect by a suitable plug with a socket connected with a source of electrical energy for conducting a current of electricity through the resistance coil 26 to render the latter incandescent and thus heat the heater 13. In practice the resistance coil 26 is arranged to produce heat of a desired degree and one that is sufficient to properly set the hair without danger of burning, singeing or otherwise injuring the hair wound upon the waving tool 10 and held within the heater, as above explained. In practice it takes about twenty minutes to properly set the hair and by using a low heat for a comparatively long time the desired waving effect and permanent setting of the hair is produced.

In order to properly hold the heater and the parts contained therein in position on the head of the subject use is made of a handle 30 of wood or similar material and attached to the top of the heater 13 approximately at the middle thereof. The upper end of the handle 30 is provided with an eye 31 to which is secured a rope, cord or other flexible connection 32 extending over

2
guide pulleys 33, 34 attached to a ceiling or other overhead support. The end of the flexible connection 32 is provided with a counterweight 35 for counterbalancing the heater and the parts mounted therein to hold the same suspended on the subject's head without exerting a pull on the hair. It will be noticed that the casing 18 adjacent the roots of the hairs of the strand is free to 10 abut against the side of the head of the subject without danger of burning the same as the said covering is not liable to be unduly heated by the heated waving tool 10.

After the lapse of about twenty minutes 15 the electricity is turned off and the heater 13 is disengaged from the wrapper 12 and then the latter is taken off after which the tool 10 is withdrawn from the strand of hair 11. The strand of hair now assumes 20 the position shown in Fig. 4, that is, the strand extends in a serpentine line in a sidewise direction, namely, in a plane approximately parallel to that of the surface of the head of the subject. This strand is now 25 moistened and combed out whereby a genuine Marcel wave effect is produced. It will be noticed that by the arrangement described the hair is not kinked, curled or crimped but is given a serpentine or a wavy 30 appearance with each hair extending in a

plane approximately parallel to the surface of the head of the subject. It will also be noted that the hair is not overheated or injured during the process of waving the hair especially as the temperature of the heater 35 is comparatively low and the hair is protected by the wrapper 12 of asbestos or similar material.

Having thus described my invention, I claim as new and desire to secure by Let- 40 ters Patent:—

In an apparatus for waving natural hair on the head, a waving tool of an approximately U-shape and upon the side members of which a strand of hair of the head is 45 adapted to be wound by passing the hair repeatedly around one side member, then between the members and around the other member to arrange the hair in a sidewise extending serpentine line, and a tubular 50 covering of a heat insulating material covering the bend of the said waving tool and terminating at its ends at the side members of the tool to hold the hair against sliding off this end of the waving tool, the said covering being adapted to abut against the side of the head of the user to protect the head against being burned by the heated tool. 55

MAX MULLER.
